(57) **CLAIM**

The ornamental design for a battery pack as shown and described.

DESCRIPTION

FIG. 1 is a perspective view of a first embodiment of a battery pack showing the new design.

FIG. 2 is a left-side view thereof.

FIG. 3 is a right-side view thereof.

FIG. 4 is a front view thereof.

FIG. 5 is rear view thereof.

FIG. 6 is a top view thereof.

FIG. 7 is a bottom view thereof.

FIG. 8 is enlarged partial view of the area indicated by "8" in FIG. 1.

FIG. 9 is enlarged partial view of the area indicated by "9" in FIG. 4.

FIG. 10 is enlarged partial view of the area indicated by "10" in FIG. 6.

FIG. 11 is a perspective view of a second embodiment of a battery pack showing the new design.

FIG. 12 is a left-side view thereof.

FIG. 13 is a right-side view thereof.

FIG. 14 is a front view thereof.

FIG. 15 is rear view thereof.

FIG. 16 is a top view thereof.

FIG. 17 is a bottom view thereof.

FIG. 18 is enlarged partial view of the area indicated by "18" in FIG. 11.

FIG. 19 is enlarged partial view of the area indicated by "19" in FIG. 14; and,

FIG. 20 is enlarged partial view of the area indicated by "20" in FIG. 16.

The dash-dash broken lines in the drawings illustrate portions of the article that form no part of the claimed design. The dot-dash broken lines in the drawings illustrate boundaries of the claim and form no part of the claimed design.

1 Claim, 16 Drawing Sheets
